UNITED STATES PATENT OFFICE.

PATRICK J. MADDEN, OF CHICAGO, ILLINOIS.

DESIGN FOR A BODY FOR SEWER-TRAPS.

SPECIFICATION forming part of Design No. 32,451, dated April 3, 1900.

Application filed February 23, 1900. Serial No. 6,311. Term of patent 7 years.

To all whom it may concern:

Be it known that I, PATRICK J. MADDEN, a citizen of the United States, residing at Chicago, in the county of Cook and State of Illinois, have invented and produced a new and original Design for the Body of a Sewer-Trap, of which the following is a specification, reference being had to the accompanying drawings, which are made a part hereof, and in 25
5 which—
10

Figure 1 is an elevation of a sewer-trap of the new design. Fig. 2 is a section thereof on the line 2 2, Fig. 1. Fig. 3 is a section thereof on the line 3 3, Fig. 2.

15 The leading essential features of the new design are a hollow oblate ovoidal part A, which forms the shell or casing for the valve, a tubular stub B, proceeding from one side of the shell A, a double elbow C, one end of 35
20 which joins one end of the shell A, and a tubular portion D, one end of which joins the other end of the elbow, the parts being shaped and arranged substantially as shown in the drawings.

A minor feature of the design is an enlargement *b* on one side of the stub B at its juncture with the shell A.

Another minor feature of the design is a substantially-cylindrical part *a* at that end of the shell A which joins the elbow C, said cylindrical part being united to the elbow by a gradually-contracted part *a'*, the outer surfaces of the parts *a a'* and the elbow merging with each other upon curved lines.

Another minor feature of the invention is a shoulder *c* at the juncture of the elbow C and tube D, said shoulder being the result of making the part D of less diameter than the part C.

What I claim as new, and desire to secure by Letters Patent, is—

The design for the body of a sewer-trap substantially as herein shown and described.

PATRICK J. MADDEN.
